UNITED STATES PATENT OFFICE

2,632,966

MULTIPLE IRONING MACHINE

John H. Leef, Minneapolis, Minn.

Original application May 1, 1948, Serial No. 24,571, now Patent No. 2,566,477, dated September 4, 1951. Divided and this application February 15, 1950, Serial No. 144,343

15 Claims. (Cl. 38—5)

1

My present invention relates to improvements in ironing or pressing mechanisms of the kind embodying a plurality of individual ironing or pressing units or machines mounted in spaced relation on a common supporting structure for common movements with respect to an operator's station; this application being filed as a division of my United States Letters Patent No. 2,566,477.

Garment ironers of the type herein described include relatively fixed pressing shoes and relatively movable pressing shoes which are conventionally manually separated for the insertion of garments therebetween and the removal of garments therefrom, and are manually brought into pressing engagement and locked therein.

The primary object of my invention is the provision of a device, wherein ironers of the above type are mounted on an endless track for movements to and from an operator's station and means for automatically opening and closing said garment ironers at timed intervals adjacent the operator's station.

Another object of my invention is the provision of means for successively and independently opening each of the ironers in a group, as set forth, as the same approaches an operator's station and means for successively and independently closing each of said ironers as it leaves the operator's station.

Another object of my invention is the provision of manually-operated means for rendering the means for closing the ironers inoperative, whereby the ironers may be cooled while in an open condition.

Another object of my invention is the provision of a plurality of ironers, as set forth, mounted for continuous and uninterrupted movements about an endless circular track, each having an ironer-closing lever engageable with means adjacent the track for automatically moving said lever to an ironer-closed position.

Another object of my invention is the provision of fluid pressure-operated mechanism mounted adjacent the track and engageable with operative levers of the ironers to successively close the ironers as each thereof leaves the operator's station.

Still another object of my invention is the provision of a plurality of ironers, as set forth, having release mechanisms permitting said ironers to open, and fluid pressure-operated mechanism mounted adjacent the track, and in spaced relation to the ironer-closing mechanism, for operating the release mechanism of said ironers to

successively open the ironers as each thereof approaches the operator's station.

Another object of my invention is the provision of control means for the fluid pressure-operating mechanism, and operating means for said control means responsive to movements of the ironers about the track to operate said control means.

A still further object of my invention is the provision of a garment ironer, as set forth, and operating mechanism therefor, which is relatively inexpensive to produce, rugged in construction, and efficient and durable in use.

Other highly important objects and advantages of my invention will become apparent from the following detailed specifications, appended claims, and attached drawings.

Referring to the drawings, wherein like characters indicate like parts throughout the several views:

Fig. 1 is a plan illustrating a group of ironers mounted on a turntable in accordance with my invention;

Fig. 2 is an enlarged fragmentary vertical section taken substantially on the line 2—2 of Fig. 1, some parts being broken away;

Fig. 3 is a still further enlarged fragmentary section taken substantially on the line 3—3 of Fig. 1;

Fig. 4 is an enlarged fragmentary detail, partly in side elevation and partly in section, taken substantially on the line 4—4 of Fig. 1;

Fig. 5 is an enlarged fragmentary detail, partly in elevation and partly in section, taken substantially on the line 5—5 of Fig. 3;

Fig. 6 is an enlarged fragmentary section taken on the line 6—6 of Fig. 3; and

Fig. 7 is a detail, partly in elevation and partly in section, taken substantially on the line 7—7 of Fig. 4.

Referring with greater particularity to the drawings, the numeral 1 indicates, in its entirety, a turntable comprising an annular supporting plate 2 secured to a concentric annular hub 3 by means of a plurality of radial arms 4. The plate

2 is reinforced by concentric annular flanges 5 and 6, the latter being in the nature of structural angle iron. Depending spaced flanges 7 form bearing brackets journaling wheels 8 for rotation upon an endless circular track 9.

Mounted fast on the annular supporting plate 2 is a plurality of circumferentially-spaced pressing or ironing devices 10, each having a relatively stationary pressing shoe 11 and a relatively movable pressing shoe 12. As shown in Fig. 2, the fixed elements 11 are mounted on circumferen-

tially-spaced pedestal-like supporting base structures 13. Each shoe 12 is provided with arms 14 rigidly secured thereto, projecting radially inwardly of the turntable 1 and pivoted at their intermediate portions to their respective bases 13, as indicated at 15. At their radially inner ends, the arms 14 are provided with the customary counterweights 16. Each of the ironers 10 have identical linkage for moving their respective movable shoes 12 from the full line position of Fig. 2 to the dotted line position thereof and vice versa. For the sake of brevity, but one of the operating linkage units will be described.

A toggle link 17 has its upper end pivoted to the arm 14 intermediate the pivot 15 and the counterweighted end 16, as indicated at 18. The lower end of the toggle link 17 is pivotally connected to a second toggle link 19, as at 20, which toggle link 19 has its lower end pivoted to the base 13, as indicated at 21. An operating lever in the form of a treadle 22 is pivotally secured to the base 13, as indicated at 23, and projects radially outwardly of the base 13 and turntable 1 through a slot 24 in the base 13. A generally vertically-disposed link 25 has its lower end pivoted to the intermediate portion 26 of the lever 22 and has its upper end pivoted to one end of a lever arm 27, as indicated at 28. The lever arm 27 is mounted for rocking movements on a rock shaft 29 extending transversely of the base 13 and having its inwardly-projected end coupled to the intermediate portion 30 of the toggle link 19 by means of a relatively short link 31, which is connected to the radially inner end of the lever arm 27, as at 32. It should be obvious, by reference to Fig. 2, that downward movement of the lever 22 will cause movements of the movable shoe 12 in the direction of the relatively fixed shoe 11 to close the ironer, as indicated by full lines. Conversely, upward movement of the lever 22 will cause movements of the movable shoe 12 in a direction away from the stationary shoe 11, as indicated by dotted lines in Fig. 2. A coil tension spring 33 has one end secured to the vertical link 25 and its opposite end anchored to the base 13, whereby to bias the lever 22 in an upward direction to move the shoe 12 in an ironer-open direction away from the relatively fixed shoe 11. A stop screw 34 limits movements of the linkage and consequent movement of the movable shoe 12 in the direction of the fixed shoe 11.

The several ironers 10 are provided with means for locking the levers 22 thereof in their depressed positions, as best shown in Figs. 2-4 inclusive and 7. In each of the several ironers 10, said means includes a laterally-projecting pin 35 adjacent the outer end of the lever 22 adapted to have sliding engagement with an arm 36 pivoted at its lower end to a bracket 37 secured to the radially outer surface of the base 13. The arm 36 is yieldingly biased in the direction of the pin 35 by means of a coil compression spring 38 and is provided with an offset portion intermediate its ends, which forms a recess 39 in which the pin 35 is seated when the lever 22 is in its extreme depressed position, as shown in Figs. 2 and 7. A release lever 40 is pivotally secured to the base 13, as indicated at 41, and extends radially outwardly of the turntable 1 at one side of the lever 22 and parallel thereto. A bell crank 42 has its intermediate portion pivotally secured to the release lever 40, as indicated at 43, and has one of its arms 44 held against vertical swinging move-

ments by means of a rigid link 45 secured thereto and to the base 13 by means of a bracket 46 (see particularly Figs. 3, 4, and 7). The other arm 47 of the bell crank 42 extends generally upwardly and is adapted to engage a laterally-projecting lug 48 on the arm 36. Downward movement of the release lever 40 causes the arm 47 to swing radially inwardly with respect to the turntable, and a consequent movement in a direction radially inwardly of the turntable of the arm 36 against bias of the spring 38, as best shown in Fig. 4. This inward movement of the arm 36 releases the laterally-projecting pin 35 from the recess 39 and allows bias of the spring 33 to move the lever 22 in an upward direction, and consequent movements of the relatively movable shoe 12 in a direction away from the relatively fixed shoe 11 to open the ironer 12. A coil tension spring 49 has one end anchored to the release lever 40 and its other end to the base 13, whereby to bias the release lever 40 in an upward direction.

For the purpose of supplying heat, preferably through the medium of dry steam, to the several movable pressing shoes 12, I provide an inlet pipe 50, the lower end of which is rotatably connected to the upper portion of a steam manifold 51 through a packing gland 52. The upper or input portion 53 of the manifold 51 is divided from the lower or exhaust portion 54 thereof by a partition 55 having therein a central drain orifice 56. A plurality of flexible inlet tubes 57 lead one each from the inlet chamber 53 of the manifold 51 to one of the movable shoes 12. The shoes 12 are each provided with flexible drain pipes or tubes 58 that are connected to the lower exhaust portion 54 of the manifold 51. The inlet tubes 57 and drain tubes 58, being flexible in nature, do not interfere with the freedom of movement of the relatively movable shoes 12. Condensate from the shoes 12 passes through the tubes 58 into the exhaust chamber 54 from whence it is removed by a drain pipe 59 through a packing gland 60. It will be seen, particularly, by reference to Figs. 1 and 2, that the manifold 51 overlies and is concentric with the hub 3 of the turntable 1 and that the flexible tubes 57 and 58 radiate outwardly from the manifold 51 to their respective shoes 12.

Continuous and uninterrupted rotary movement at a relatively slow speed is imparted to the turntable 1 by a motor 61 (see Fig. 1) which drives a shaft 62 through reduction gearing not shown but contained within a gear box 63. A sprocket wheel 64 is secured fast to the shaft 62 and positively drives a link chain 65 which extends about and is carried within a channel 66 formed by the outer peripheral portion of the plate 2 and the flange 6. The chain 65 is maintained in frictional driving contact with the flange 6 by means of an idler pulley 67 journalled to one arm of a bell crank 68 that is pivoted to a stationary quadrant 69. Pin and socket connections 70 of conventional design are utilized to maintain the idler 67 in a position to tighten the link chain 65. Obviously, moving the bell crank 68 in a counter-clockwise direction with respect to Fig. 1 will loosen the link chain 65 in the channel 66. This arrangement provides an inexpensive but very satisfactory drive for the turntable 1. It will be observed that the turntable 1 rotates in a clockwise direction with respect to and as shown by arrows in Fig. 1.

I provide means adjacent the periphery of the turntable 1 and to one side of an operator's

station X for automatically and successively depressing the several treadle levers 22 upon rotation of the turntable 1 to close their respective ironers 10. The lever-depressing means is in the nature of a fluid pressure-operated cylinder 71 and a piston 72 mounted for reciprocal movements therein. The cylinder 71 is vertically axially held in a position overlying the path of travel of the free end of the lever 22 by means of a supporting frame 73 rigidly secured to the floor or other stationary supporting means by bolts or the like 74. A piston plunger rod 75 extends downwardly through the lower end of the cylinder 71 and is provided at its lower end with a presser foot 76, which extends generally in the direction of movement of the turntable 1, and which is adapted to be moved into and out of the path of travel of the several levers 22 about the track and to engage rollers 77 mounted on the outer ends of the lever 22 by means of bearing brackets 78. The piston 72 and piston rod 75 are yieldingly biased in a direction away from engagement with the several rollers 77 by means of a coil compression spring 79. Fluid under pressure is admitted to one end of the cylinder 71 from a source of fluid pressure not shown, through conduit means 80. A three-way valve 81 is interposed in the conduit means 80 and is secured to the supporting frame 73 by means of machine screws or the like 82. The valve 81 may be of any particular type, but preferably and as shown is provided with a rotary valve plug 83, which is chambered to allow fluid under pressure to pass therethrough from the source of pressure to the cylinder 71. The plug 83 may be turned to allow passage of fluid from the cylinder 71 to atmosphere through a port 84 in the valve 81. The plug 83 extends outwardly through the body of the valve 81 and has rigidly secured to the outer end thereof a pair of circumferentially-spaced movable finger members 85 and 86 that are adapted to engage, upon rotation of the turntable 1, valve-operating abutments 87 and 88 respectively. The abutments 87 and 88 are in the nature of lugs or pins mounted one each on the base 13 in vertically and horizontally-spaced relationship. It will be understood that each ironer 10 is provided with a pair of abutments 87 and 88. I also provide a manually-controlled shut-off valve 89 in the conduit means 80 between the source of pressure and the valve 81 and located at a point within easy reach of the operator of the machine.

Movement of the turntable 1 in a direction from the right to the left with respect to Fig. 6 causes the abutment 88 to engage the movable member 86 and move the same to a point where the chamber of the plug 83 will admit fluid under pressure from the source of pressure to the cylinder 71. Pressure within the cylinder 71 will be sufficient to move the piston 72 against bias of the spring 79 and cause the foot 76 to engage the roller 77 passing thereunder and depress the lever 22 to its extreme downward position where it will be locked by the mechanism heretofore described. Continued movement of the turntable from the right to the left, with respect to Fig. 6, causes the abutment 87 to engage the valve-operating member 85 and move the same and the plug 83 to a position whereby fluid is allowed to flow from the cylinder 71 to atmosphere through the port 84 under bias of the spring 79 against the piston 72. The valve-operated members 85 and 86 are so arranged that, when the abutment 88 has moved the member 75

86 to its desired position, the outer end of the member 86 will be moved upwardly to a point where the abutment 88 may pass thereunder. This movement of the member 86 causes the member 85 to be moved to a point where it may be engaged by the abutment 87 upon continued movement of the turntable. Similarly, when the abutment 87 has moved the member 85 to a point where fluid is allowed to escape from the cylinder 71 to atmosphere through the valve 81, the outer end of the member 85 will become depressed to a point where the abutment 87 may pass thereover.

Fluid pressure-operated means for successively and independently releasing the several levers 22 from their locked depressed positions comprises a fluid pressure cylinder 90, a piston 91 mounted for reciprocation therein, and a piston plunger rod 92 connected to said piston 91 and projecting axially outwardly of the cylinder 90, and operating connections therebetween and the release lever 40. The cylinder 90 is pivotally connected, as indicated at 93, to a stationary supporting frame 94, which is located adjacent the turntable 1 and at the opposite side of the operator's station X from the frame 73 and the structure carried thereby. A rocker arm 95 is intermediately pivoted, as indicated at 96, to the upper end of the supporting frame 94, and has its outer end pivotally connected to the upper end of the piston plunger rod 92, as at 97. At its inner end, the rocker arm 95 is formed to provide bearings which journal a roller 98 that overlies the path of travel of the release lever 40. Fluid under pressure from a source not shown is admitted to the cylinder 90 through a conduit 99 and a three-way valve 100, said valve being secured fast to the supporting frame 94 by means of screws or the like 101. The valve 100 is similar to the valve 81, having therein a rotary plug 102, which is chambered to allow fluid under pressure to be admitted to the interior of the cylinder 90 through the conduit 99. The plug 102 is rotatable, whereby to allow fluid to escape from the cylinder 90 through the conduit 99 to atmosphere through a port 103 in the valve 100. The plug 102 extends outwardly of the valve body 100 and terminates in a pair of circumferentially-spaced radially-projecting arms 104 and 105, which are adapted to be engaged and moved by respective abutment lugs or pins 106 and 107 projecting radially outwardly from the turntable 1. It should be noted that the roller 98 is adapted to be moved by the piston 91 into and out of the path of travel of the several release levers 40 about the track, and that there is provided a pair of abutments 106 and 107 for each ironer 10.

As a given ironer 10 approaches the operator's station X, the abutment lug 107 for its respective ironer 10 will engage and move the valve-operating arm 105 and thereby cause rotation of the plug 102 to a position to permit fluid under pressure to enter the cylinder 90. Resultant movement of the piston 91 and the plunger rod 92 in an upward direction will cause rocking movement of the rocker arm 95 and engagement of the release lever 40 by the roller 98. Continued downward movement of the roller 98 will cause the release lever 40 to disengage the locking means from the lever 22 and allow the same to move upwardly to the dotted line position of Figs. 2 and 4, wherein it will be seen that the movable shoe 12 connected therewith is moved away from its cooperating relatively fixed shoe 12. As the abutment 106 moves from the right to the left

with respect to Fig. 7 upon rotary movement of the turntable 1, the plug 102 will be rotated to a point where the fluid will be allowed to escape from the cylinder 90 to atmosphere through the port 103. As the abutment 106 progresses further from the right to the left, it will pass over the outer end of the arm 104 and the operating arm 105 will be moved to its dotted line position of Fig. 7, where it will be engageable with the next successive abutment 107.

When it is desired to suspend operations of the machine, the shut-off valve 89 is manipulated to prevent fluid under pressure from entering the cylinder 71. Thus, the piston 72 and plunger rod 75 will be rendered inoperative to depress the several levers 22; and, under continued rotation of the turntable 1, all ironers will be placed in an open condition and remain so until the shut-off valve 89 is again opened. This arrangement permits shutting down of the ironing machine without danger of the heated shoes 12 scorching the conventional cloth covering and padding on the stationary shoes 11.

It is understood that the ironers 10 herein disclosed are in themselves old in the art. I have found that, by mounting these ironers on a turntable as shown and automatically controlling the movements of the movable shoes with respect to the relatively fixed shoes thereof, I have been able to effect a great savings in time and labor in the ironing of various garments on a production scale.

While I have shown and described a commercial embodiment of my improved ironing machine, it will be understood that the same is capable of modification without departure from the spirit and scope of the invention as defined in the claims.

What I claim is:

1. In an ironing machine of the class described, an endless track, a supporting structure mounted and guided for travelling movements about said track, driving mechanism for imparting movements to said supporting structure about said track, a normally open garment ironer mounted on said supporting structure and comprising cooperating pressing shoes mounted for relative movement between a normally open position and a closed position, an operating lever carried by the supporting structure for movements with respect thereto, operating linkage associated with said lever and one of said pressing shoes and responsive to movement of said lever in one direction to close the ironer, and means adjacent the track for moving said operating lever toward its ironer-closed position, said means comprising a presser element, means mounting said presser element for lever-operating movements into and out of the path of travel of said lever about said track, and power-operated mechanism for imparting lever-operating movements to said presser element to operate said lever to close the ironer.

2. The structure defined in claim 1 in further combination with control means for said power-operated mechanism, said control means comprising an abutment mounted on said supporting structure for common movements therewith about said track, and control mechanism including a movable member lying in the path of travel of said abutment and responsive to engagement therewith to render said power-operated mechanism operative.

3. In an ironing machine of the class described, an endless circular track, a supporting structure

mounted and guided for travelling movements about said track, driving mechanism for imparting continuous and uninterrupted movement to said supporting structure about said track, a normally open garment ironer mounted on said supporting structure and comprising cooperating pressing shoes mounted for relative movement between a normally open position and a closed position, an operating lever carried by the supporting structure for movements with respect

thereto, operating linkage associated with said lever and one of said pressing shoes and responsive to movement of said lever in one direction to close the ironer, and means adjacent the track for moving said operating lever toward its ironer-closed position, said means comprising a presser foot, a relatively stationary supporting structure mounting said presser foot for lever-operating movements into and out of the path of travel of said lever about the track, and power-operated mechanism for imparting lever-operating movements to said presser foot to operate said lever to close the ironer.

4. The structure defined in claim 3 in which said presser foot is elongated generally in the direction of travel of said operating lever about said track.

5. In an ironing machine of the class described, an endless circular track, a supporting structure mounted and guided for travelling movements about said track, driving mechanism for imparting continuous and uninterrupted movement to said supporting structure about said track, a normally open garment ironer mounted on said supporting structure and comprising cooperating pressing shoes mounted for relative movement between a normally open position and a closed position, an operating lever carried by the supporting structure for movements with respect thereto, operating linkage associated with said lever and one of said pressing shoes and responsive to movement of said lever in one direction to close the ironer, and fluid pressure-operated means adjacent the track for moving said operating lever toward its ironer-closed position, said means comprising a presser foot, a relatively stationary fluid pressure cylinder adjacent said track, a cooperating piston plunger mounting said presser foot for lever-operating movements into and out of the path of travel of said lever about the track, and control means for said fluid pressure-operated means, said control means including a control element on said supporting structure and a cooperating element located in the path of travel of said control element, whereby said presser foot is moved in definite timed relation to travelling movement of said lever about the track.

6. The structure defined in claim 5 in which said control means comprises an abutment mounted on said supporting structure for common movements therewith about said track, a control valve supported adjacent the said track, and a valve-operating arm operatively associated with said valve, said arm normally lying in the path of travel of said abutment and responsive to engagement therewith to cause said valve to admit fluid under pressure to said cylinder.

7. The structure defined in claim 5 in further combination with manually-operated means for rendering the fluid pressure-operated means inoperative to move said presser foot into the path of travel of the lever about said track.

8. In an ironing machine of the class described, an endless circular track, a supporting structure

mounted and guided for travelling movements about said track, a driving mechanism for imparting continuous and uninterrupted movement to said supporting structure about said track, a normally open garment ironer mounted on said supporting structure and comprising cooperating pressing shoes mounted for relative movement between a normally open position and a closed position, an operating lever carried by the supporting structure for movements with respect thereto, operating linkage associated with said lever and one of said pressing shoes and responsive to movement of said lever in one direction to close the ironer, means adjacent the track for moving said operating lever toward its ironer-closed position, said means for moving said lever to its ironer-closed position comprising a presser foot, a relatively stationary supporting structure mounting said presser foot for lever-operating movements into and out of the path of travel of said lever about said track, and power-operating mechanism imparting lever-operating movements to said presser foot to close the ironer, means locking the lever in said ironer-closed position, and mechanism for unlocking said operating lever to permit movements thereof in a direction to open said ironer, said unlocking mechanism including a release lever pivoted to said supporting structure, a movable member adjacent said track in circumferentially-spaced relationship to said presser foot, a relatively stationary support mounting said movable member for release lever-operating movements into and out of the path of travel of said release lever about said track, and power-operated mechanism for imparting release lever-engaging movements to said movable member.

9. The structure defined in claim 8 in further combination with yielding means biasing said operating lever toward an ironer-open position.

10. In an ironing machine of the class described, an endless circular track, a supporting structure mounted and guided for travelling movements about said track, driving mechanism for imparting continuous and uninterrupted movement to said supporting structure about said track, a normally open garment ironer mounted on said supporting structure and comprising cooperating pressing shoes mounted for relative movement between a normally open position and a closed position, an operating lever carried by the supporting structure for movements with respect thereto, operating linkage associated with said lever and one of said pressing shoes and responsive to movement of said lever in one direction to close the ironer, fluid pressure-operated means adjacent the track for moving said operating lever toward its ironer-closed position, said means comprising a presser foot, a relatively stationary fluid pressure cylinder adjacent said track, a cooperating piston plunger mounting said presser foot for lever-operating movements into and out of the path of travel of said lever about the track, and control means for said fluid pressure-operated means, said control means including a control element on said supporting structure and a cooperating element located in the path of travel of said control element, whereby said presser foot is moved in definite timed relation to travelling movement of said lever about the track, latch means locking the operating lever in said ironer-closed position, and mechanism for unlocking said operating lever to permit movements thereof in a direction to open said ironer, said unlocking mechanism comprising a release lever operatively associated with said

locking means, a movable member, a relatively stationary support mounting said movable member for release lever-operating movements into and out of the path of travel of the release lever about said track, and power-operated mechanism for imparting release lever-engaging movements to said movable member, said movable member being in spaced relation to said presser foot in the direction of travel of said ironer-supporting structure.

11. The structure defined in claim 10 in which said power-operated mechanism comprises a fluid pressure cylinder, said movable member including a piston plunger operatively associated with said last-mentioned cylinder, and in further combination with a control valve for said power-operated mechanism, and means carried by the ironer-supporting structure for operating said control valve upon movements of said supporting structure about said track.

12. The structure defined in claim 10 in further combination with yielding means biasing said operating lever toward an ironer-open position.

13. In a machine of the class described, an endless circular track; a turntable rotatably mounted on said track; mechanism for imparting continuous and uninterrupted movement to said turntable on said track; a plurality of normally open garment ironers mounted on the turntable in circumferentially spaced relationship; each of said garment ironers comprising cooperating pressing shoes mounted for relative movement between a normally open position and a closed position, a plurality of pivoted operating levers one for each of said ironers, linkage operatively associated with each operating lever and a respective one of said shoes, each said linkage being responsive to movement of its respective lever in one direction to close the ironer, yielding means biasing each lever and linkage toward an ironer-open position, and latch means locking each lever in an ironer-closed position; means adjacent the track for successively and independently moving each operating lever to its ironer-closed position; said last-mentioned means comprising a presser foot, a relatively stationary supporting structure mounting said presser foot for lever-operating movements into and out of the path of travel of said lever about the track, and power-operated mechanism imparting lever-operating movements to said presser foot; and mechanism for successively and independently unlocking the operating levers upon rotation of the turntable to permit movements of the levers in a direction to open their respective ironers; said unlocking mechanism including a plurality of release levers one each operatively associated with each of said locking mechanisms, a movable member, a relatively stationary support mounting said movable member for release lever-operating movements into and out of the path of travel of said release levers about said track in circumferentially-spaced relationship to said presser foot, and power-operated mechanisms for imparting release lever-engaging movements to said movable member.

14. In an ironing machine of the class described; an endless circular track; a turntable rotatably mounted on said track; mechanism for imparting continuous and uninterrupted movement to said turntable about said track; a plurality of normally open garment ironers mounted on said turntable in circumferentially spaced relationship, each of said ironers comprising cooperating pressing shoes mounted for relative

11

movement between a normally open position and a closed position, a plurality of pivoted operating levers one for each of said ironers, linkage operatively associated with each operating lever and a respective one of said shoes each said linkage being responsive to movement of its respective lever in one direction to close the ironer, spring means yieldingly biasing each lever and linkage toward an ironer-open position, and latch means locking each lever in an ironer-closed position; fluid pressure-operated means adjacent the track for successively and independently moving each operating lever to its ironer-closed position; said last-mentioned means comprising a fluid pressure cylinder, a stationary support mounting said cylinder, a piston plunger cooperating with said cylinder, and a presser foot mounted on the free end of said plunger and movable therewith to and out of the path of travel of said operating levers about said track; and fluid pressure-operated means for successively and independently unlocking the operating levers upon rotation of the turntable to permit movements of the levers in a direction to open said ironers; said unlocking means including a plurality of release levers one each operatively associated with each of said locking mechanisms, a fluid pressure cylinder

12

rigidly mounted adjacent said track in circumferentially-spaced relationship to said first-mentioned cylinder, and a piston plunger mounted in said last-named cylinder for release lever-operating movements into and out of the path of travel of said release levers about said track.

15. The structure defined in claim 14 in further combination with independent control means for each of said fluid operated means, each of said control means comprising a stationary control valve adjacent said track, a plurality of abutments one each associated with each of said ironers for movements therewith about the track, and a valve-operating arm normally lying in the path of travel of said abutments and responsive to engagement therewith to cause said valve to admit fluid under pressure to the cylinder associated therewith.
